ROTARY STRIPING WHEEL PAINT STRIPERS

Joseph R. Benkowski, Chicago, Ill., assignor to Wendell Manufacturing Company, Chicago, Ill., a corporation of Illinois

Application January 27, 1955, Serial No. 484,422

1 Claim. (Cl. 15—132.5)

This invention relates to a rotary striping wheel paint stripers of the general character which are illustrated in the Coombs Patents Nos. 2,122,858 and 2,582,861.

The rotary striping wheel paint stripers which are illustrated in Coombs Patents Nos. 2,122,858 and 2,582,861 generally include a striping head to which is detachably mounted a paint storage container in the form of a collapsible tube container, bottle, for holding paints or similar surface striping materials. While the paint stripers shown in the aforesaid patents are satisfactory for their intended purposes, it has been found from experience in the use thereof that under one particular operating condition, namely, when attempting to stripe upon a vertical wall or like surface, it did not operate satisfactorily and it is a principal object of the present invention to provide a paint stiper which in use overcomes that difficulty, namely, the difficulty experienced in the use of prior striping devices when striping upon a vertical surface.

Thus in the use of the rotary striping wheel paint stripers, such as are disclosed in the aforesaid Coombs Patents Nos. 2,122,858 and 2,582,861, it is sometimes desirable to apply a paint or similar stripe upon a vertical wall surface, or upon the vertical surface of a piece of wood furniture, or the like, and for this purpose it becomes necessary to hold the striping head and striping wheel unit in a generally horizontal position against the vertical surface, but when so arranged, the paint storage container attached to the striping wheel will also be arranged in a horizontal position, with the result that the paint does not flow freely therefrom through the striping head and onto the peripheral surface of the striping wheel unit.

Accordingly, an object of the present invention is to provide a new and improved rotary striping wheel paint stiper which is adapted to overcome the aforesaid difficulty experienced in the use of the paint stripers disclosed in the aforesaid Coombs patents, and to provide a rotary striping wheel paint stiper which may be effectively employed in striping paint or like striping material on a vertical wall surface such, for example, as upon a vertical wall surface or upon the surface of a piece of furniture or the like.

Another object of the invention is to provide a new and improved rotary striping wheel paint stiper, which is so designed and constructed that in the use thereof, when striping upon a vertical surface, the striping wheel and striping wheel holder jaw head or assembly embodied therein may be swivelly moved relative to and upon the storage container and the coupling member by means of which the striping wheel and striping wheel holder jaw assembly are coupled to the storage container so that the striping wheel and striping wheel holder jaw assembly may be arranged at an acute angle relative to the storage container and coupling member so that the paint or similar surface striping material will readily flow from the storage container by gravity through the striping wheel and striping wheel holder jaw assembly onto the periph-

2

eral surface of the rotary striping wheel unit, even though the striping wheel is arranged in a generally horizontal plane for striping upon a vertical wall or like vertical surface.

5 A further object of the invention is to provide a new and improved rotary striping wheel paint stiper which, while being adapted to overcome the aforesaid difficulty experienced in the use of prior rotary striping wheel paint stripers is likewise adapted for general paint striping use.

10 Other objects will appear hereinafter.

In the drawings:

Fig. 1 is an elevational view of the new rotary striping wheel paint stiper, showing the same as used for striping paint or like material upon a horizontal surface;

15 Fig. 2 is an elevational view of the striping head assembly embodied in the new rotary paint striping wheel tool;

Fig. 3 is a sectional plan view on line 3—3 of Fig. 1;

20 Fig. 4 is an elevational view of one of the striping wheel and holder jaws therefor which are embodied in the new striping wheel tool;

Fig. 5 is an elevational view of one of the striping wheel holder jaws which are embodied in the new striping wheel tool, as seen from the inner side thereof, and with the striping wheel removed therefrom;

25 Fig. 6 is an elevational view of the striping wheel holder jaw shown in Fig. 5, as seen from the outer side thereof;

Fig. 7 is an elevational view, partly in section, of part of the neck of the storage container and the coupling member illustrating the manner in which the striping wheel head is mounted in position of use in the new striping tool, being broken away to show the arrangement of the parts;

30 Fig. 8 is an elevational view showing the manner in which the new rotary striping wheel paint striping tool may be used for striping upon a vertical wall surface, or like vertical surface; and

35 Fig. 9 is an exploded view, partly in section, showing the various parts embodied in the new rotary striping wheel paint stiper tool.

A preferred embodiment of the new rotary striping wheel paint stiper tool is illustrated in the drawings, where it is generally indicated at 10, and comprises a paint storage container or receptacle in the form of a bottle 11, which may be made of glass, resinous plastic, or other material, and which has a reduced externally threaded neck portion 23 which is adapted to be threaded into the internally threaded portion of a frusto-conically shaped coupling member 13. The new rotary striping wheel paint striping tool 10 also includes a striping wheel and striping wheel holder jaw assembly 14 which includes a pair of rotary striping wheel holder jaws 15, each of which includes a generally hemispherical swivel head portion 16, and a depending lower portion 17, from which a paint-supporting depending flange 18 extends.

45 The rotary striping wheel holder jaws 15 are held together in assembled relationship by a pintle 19 which extends through and is mounted on the depending flanges or extensions 18 and a pair of rotary striping wheels 20 which are mounted on the pintle 19 in assembled side by side relationship, each of the rotary striping wheels 20 having a knurled peripheral surface, as shown.

50 Each of the generally hemispherical shaped swivel head portions 16 has a centrally arranged recessed groove 21 formed therein on its inner surface and the lower portion 17 of each wheel-holding jaw 18 has a recessed groove 22 formed therein on its inner surface, and these grooves 21 and 22 cooperate to form a central longitudinal passage through the striping wheel and holder jaw assembly 14 when the parts are arranged in assembled position of use so as to conduct paint or like striping material from the

storage container 11 onto the peripheral surface of the rotary striping wheels 20.

A gasket 24 is arranged in the coupling member 13 between the lower or inner edge of the neck 23 of the storage container 11 and the swivel head portions 16 of the striping wheel holder jaws 15, and this gasket 24 has a centrally arranged opening 25 formed therein.

A guide arm member 26 may be adjustably mounted in a boss 27 which is attached to one side of the coupling member 13, and the guide arm 27 may be clamped in position of use by a set screw 28 which is mounted in the boss 27.

In the use of the new rotary wheel striping tool, the jaw holder members 15 may be arranged in assembled side by side complementary relationship, and on the pintle 19, as shown in Fig. 2, and the parts, so arranged, may be extended through the frusto-conical shaped coupling member 13 from the larger upper end portion thereof into the lower end portion thereof so that the swivel head portions 16 thereof will bear against the inner wall surface of the said frusto-conical shaped coupling 13. When the parts are so arranged the grooves 21 and 22 cooperate to form a central bore or passage through the striping wheel and striping wheel holder jaw assembly with the outlet of this passage opening above the serrated or knurled surfaces of the striping wheels 20 (Figs. 7 and 9).

The gasket 24 may then be arranged in position of use above the swivel head portion 16 of the holder jaw members 15, whereupon the storage container 11 may be filled with suitable paint or other like surface-striping material. The coupling member 13, with assembled striping head assembly 14, is then screwed onto the externally threaded portion 23 of the storage container bottle 11, whereupon the parts will be arranged in assembled position, as shown in Fig. 7 of the drawings.

In the use of the new rotary wheel striping tool, the same may be employed in the manner illustrated in the Coombs Patents Nos. 2,122,858 and 2,582,861 to stripe paint or other surface-striping material, in the form of lines, or otherwise, such, for example, as a piece of furniture or other materials, and such a use of the new striping tool is illustrated in Fig. 1 of the drawings. When so arranged, the paint or like surface-striping material from the storage container or receptacle 11 will flow, by gravity, downwardly through the externally threaded neck portion 23 of the storage container 11, through the central opening 25 in the gasket 24 and into the central bore or passage 21-22 formed in the striping wheel and striping wheel holder jaw assembly 14 by the cooperation of the grooves 21 and 22, and thence onto the external surfaces of the serrated striping wheel 20, by which the paint or other surface-striping material is conveyed onto the surface or work 30 over which the new striping wheel tool may be moved, as shown in Fig. 1.

As hereinbefore pointed out, it happens that in the use of rotary paint striping tools of the character shown in the aforesaid patents, it is desirable to stripe upon a vertical wall or like surface, such as upon a vertical surface of a piece of furniture, or the like, and the present invention has the advantage over the striping wheel tools shown in the aforesaid patents which enables this to be done in the manner illustrated in Fig. 8 of the drawings. Thus, as will be seen by reference to Fig. 8, in order to provide a paint stripe or the like, on the vertical surface 29, such as upon a vertical wall or the vertical surface of a piece of furniture or the like, this may be accomplished by slightly loosening or partially unscrewing the externally threaded neck portion 23 of the storage container or receptacle 11 in the coupling member 13 and then moving the swivel head portion 16 of the striping wheel holder jaws 15 in the coupling member 13 so that the striping wheel holder jaws and striping wheel assembly 14 are arranged at an acute angle relative to the axes of the storage container 11 and coupling member 13, as shown in Fig. 8. The new striping tool, with the parts

thus arranged, may then be arranged in the position in which they are shown in Fig. 8, with the striping wheel jaw holder and striping wheel assembly 14 arranged in a generally horizontal position relative to the vertical surface 29 to be striped and with the coupling member 13 and the storage container 11 arranged at an acute angle relative to the generally horizontal axes of the striping wheel holder jaw and striping wheel assembly 14, as shown in Fig. 8.

When the parts are thus arranged in the manner shown in Fig. 8, the paint or like surface-striping material will flow by gravity from the storage container 11, through the externally threaded neck portion 23 thereof, through the central aperture 25 in the gasket 24, through the central passage 21-22 in the striping wheel holder jaws 15 and thence, by gravity, onto the serrated peripheral surfaces of the striping wheels 20, which may be moved over the vertical surface 29 to complete the striping operation.

It will be noted that when the parts of the new striping wheel tool are arranged as in Fig. 8, the force of gravity allows the paint or like striping material to flow from the storage container, and through the passage 23-25-21-22 onto the knurled or peripheral surface of the striping wheels 20, whereas if the storage container 11 was arranged on the same general axes as the striping wheel holder jaw and striping wheel assembly 14 the paint or like striping material in the storage container would not flow readily or adequately from the storage container 11 through the passage 23-25-21-22 onto the peripheral surfaces of the striping wheels 20 in a manner sufficient to perform satisfactory paint striping.

It will also be noted that the parts of the new striping tool may be readily disassembled for cleaning of the parts after each use thereof or for repair, as and when desired.

It will thus be seen from the foregoing description, considered in conjunction with the accompanying drawings, that the present invention provides a new and improved rotary striping wheel paint striping tool having the desirable advantages and characteristics, and accomplishing its intended object, including those hereinbefore pointed out, and others which are inherent in the invention.

I claim:

45 A striping tool comprising a storage container for fluid surface striping material, a striping wheel holder jaw assembly, a tubular coupling member detachably coupling said striping wheel holder jaw assembly to said storage container, and having in its lower part an annular seat of inner spherical curvature, the storage container having a lower outlet end portion detachably mounted in the upper part of the coupling member, the striping wheel holder jaw assembly including a pair of complementary oppositely disposed elongate striping wheel holding jaws, a striping wheel unit rotatably mounted upon and between lower end portions of said striping wheel holder jaws, said striping wheel holding jaws each having above the striping wheel unit a substantially flat inner surface, said flat inner surfaces fitting one against the other and each having a centrally arranged longitudinally extending groove therein, said grooves of the wheel holding jaws cooperating to complete a centrally arranged longitudinal passage through the striping wheel holder jaw assembly and tubular coupling member from the lower outlet end portion of the storage container onto the peripheral surface of said striping wheel unit, and the striping wheel holding jaws each having at its upper part a substantially hemispherical outer face portion, said hemispherical outer face portions of the wheel holding jaws being disposed and held within the lower portion of the coupling member in engagement with the seat therein and cooperating with said seat and with each other to provide a universal ball joint mounting for the striping wheel holder jaws, means for adjustably holding the hemispherical face portions in engagement with said seat,

said ball joint mounting providing for positioning the storage container with its longitudinal axis extending perpendicular to the axis of the striping wheel in line with the longitudinal axis of the wheel holder jaw assembly and also for angular adjustment of the storage container relative to the wheel holder jaw assembly so that when the latter is in a nearly horizontal position, the storage container will be inclined upwardly relative thereto and striping material will readily flow by gravity from the storage container through the wheel holder assembly to 10 the peripheral surface of the striping wheel unit.
